UNITED STATES PATENT OFFICE.

EDWARD S. PALMBLA, OF WAUKEGAN, ILLINOIS.

HYDRAULIC CLUTCH.

Application filed June 17, 1925. Serial No. 37,689.

My invention relates to hydraulic clutches involving relatively rotatable members so constructed that, under control of the operator, these members may be clutched at will through the medium of liquid imprisoned therebetween.

My primary object is to provide a novel, simple and positively operating clutch mechanism of the general type referred to, which shall be positive in operation and not be liable to impairment in use; to provide a novel, simple and positively operating mechanism operating automatically to avoid grabbing of the clutch, while permitting a quick unclutching action; to provide a construction wherein friction between the relatively rotatable portions of the clutch mechanism in the unclutched condition thereof shall be reduced to the minimum; and generally, to so improve upon mechanisms of this general character that they will be better adapted to perform the functions for which they are provided.

Referring to the accompanying drawings:—

Figure 1 is an end view of my improved clutch mechanism, the driven shaft being shown in section, and the clutch-operating mechanism, being shown in dotted lines. Figure 2 is a section taken at the line 2—2 on Fig. 1 and viewed in the direction of the arrows, the clutch-operating means, the drive-shaft, and fly wheel carried thereby, and to which one element of the clutch mechanism is connected and the braking means for the driven shaft, being as shown by dotted lines. Figure 3 is a section taken at the line 3—3 on Fig. 2 and viewed in the direction of the arrows. Figure 4 is a section taken at the line 4—4 on Fig. 2 and viewed in the direction of the arrows. Figure 5 is a section taken at the line 5—5 on Fig. 2 and viewed in the direction of the arrows. Figure 6 is a fragmentary face view, with certain parts shown in section, of the blade-equipped member forming a part of the clutch mechanism. Figure 7 is an enlarged fragmentary sectional view taken at the line 7—7 on Fig. 4 and viewed in the direction of the arrows; and Figure 8, a similar view taken at the line 8 on Fig. 5 and viewed in the direction of the arrow.

Referring to the particular illustrated embodiment of my invention, one end of the crank-shaft of an automobile engine is represented at 9 and is shown as carrying a fly

wheel 10 bolted thereto by bolts 11 in accordance with common construction, the fly wheel 10 being formed with an annular flange 12 in accordance with common construction.

The driven shaft, which is to be controllably clutched to the drive-shaft 9, is represented at 13, this shaft being in alignment with the shaft 9 and provided with a stub-shaft portion 14 which is journaled in a socket 15 extending through the fly wheel 10 and into the adjacent end of the shaft 9.

My improved clutching mechanism shown as interposed between the fly wheel 10 and the driven shaft 13 comprises a circular shell member 16 which snugly fits into the recess provided by the flange 12 in the face of the fly wheel 10, the outer marginal portion of the member 16 being provided with an annular outwardly-extending flange 17 which overlies the end surface of the flange 12. The assembled fly wheel 10 and shell 16 are provided with a cover plate 18 which fits at its circumferential margin flatwise against the flange 17, these three parts being rigidly held together by means of screw bolts 19.

The shell 16 is formed with a disk-like portion 20 at which it fits against the body of the fly wheel 10, and an annular flange portion 21 at its circumferential edge carrying the flange 17. The flange 21 is thickened at its base-portion, as represented at 22, this thickened portion being so shaped as to present a circular inner surface, as represented at 23, eccentrically disposed to the axis of the driven shaft 13. The portion 22 is cored out to provide, at the thicker part of this portion, a chamber 24 which extends from 25 to 26 and opens laterally into the space beyond this thickened portion 22, through the arcuate slot, or port, 27 and into the space surrounded by the thickened portion 22 through an arcuate slot 28, forming a port, in the inner wall of this chamber located in a different position circumferentially of the flange 17 than that occupied by the slot 27.

The portion 20 of the shell 16 is provided at its inner marginal edge with an inset portion 29 containing a groove 30 in its outer face into which the heads of the screws 11 extend and presenting at its outer circumference the circular surface 23^a concentric with the eccentrically-disposed circular surface 23 of the flange 21, the portion 29 con-

taining an opening 31 concentric with the axis of the driven shaft 13.

Surrounding the shaft 13 and keyed thereto is a rotary member 33 located within the shell 16 and comprising a hub portion 33^a at which this member is connected with the shaft 13 with an interposed steel bushing 32 at one end thereof splined to the hub 33^a. The rotary member 33 also comprises 10 spoke portions 34, shown as four in number and equidistantly spaced, though the number thereof may be varied if desired, and a sectional rim-portion 35 concentric with the axis of the shaft 13. The sections of 15 the rim portion 35 are located between adjacent ones of the spokes 34 and each is formed of a peripheral ring-portion 36 and side flanges 37 and 38, these flanges forming with the ring-portion 36, segmental 20 channels between the spokes about the inner periphery of the member 33.

The outer ends of the spokes 34, the opposite sides of which extend flush with the outer surfaces of the flanges 37 and 38, respectively, are cut away at one side, as indicated of one of the spokes 34 at 39, to permit the shell 16 to freely rotate relative to the member 33 when the latter is not clutched to the shell 16, and each of these 30 spokes contains a radially disposed slot 40 opening through the outer periphery of the member 33 and extending parallel with the axis of this member, these slots opening into radially-disposed bores 41 in the spokes.

Reciprocally mounted in the slots 40 and extending radially beyond the rim of the member 33, are blades 42, forming pistons, each of a shape and size to have sliding fit in the groove-portion of the shell 40 bounded by the surface 23, and the outer circumferential surface of the member 33 and the disk-like portion 20 between the surfaces 23 and 23^a, the outer edge-surfaces of the blades 42, as also the outer surface of 45 the flange 38, being flush with the outer surface of the thickened portion 22 of the rim of the shell 16. To avoid displacement of the blades 42 they are provided with stems 43 which slide radially in the bores 41 of 50 the spokes.

It may here be stated that the drive of the driven member 13 from the drive-member 9 is effected by the clutching of the member 33 to the shell 16 through the medium of liquid, as for example oil, confined in the space between adjacent ones of the blades 42 coating with the eccentric surfaces 23 and 23^a. The spaces between adjacent 55 blades are open at the right hand side of the rotary member 33, and to effect the clutching of the parts as stated, this space must be closed, under control, and to permit of such closing I provide a ring formed of a 60 pair of concentric ring-sections 44 and 45 which together close the open side of the

space referred to when moved into the position shown in Fig. 2. The ring-section 44 fits flatwise against, and is rigidly secured to, a ring 46, which latter is movable toward and away from the space in which the 70 blades 42 are located.

The ring-section 44 is annularly recessed, as indicated at 47 at the inner peripheral portion of the face thereof which flatwise opposes the ring 46, to provide an annular flange 48, and the ring-section 45 is annularly recessed at the outer peripheral portion of the surface thereof opposite that which flatwise opposes the ring 46, as represented at 49, to form an annular flange 50. The ring-sections 44 and 45, which extend into an annular recess 51 in the face of the ring 46, mutually overlap at their flanges 48 and 50, these flanges being of such width that when these ring sections extend in the space-closing position shown in Fig. 2, they will be spaced apart as shown.

The structure formed of the rings referred to cooperates with means tending to 90 yieldingly force this structure out of space-closing position, namely, to the right in Fig. 2, these means comprising studs 52 carried by the ring 46 and sliding in sockets 53 in the thickened rim-portion of the shell 16, coil springs 54 being confined between these studs and the inner walls of the recesses 53 and tending to move the ring-structure referred to to the right as stated.

Means are provided for yieldingly forcing the ring-section 45 to the left in Fig. 2, 100 these means comprising studs 55 carried by this ring-section and sliding in sockets 56 in the ring 46, coil springs 57 located in these sockets and confined between the end walls thereof and the inner ends of the studs 55 exerting a force yieldingly pressing the ring-section 45 to the left as stated.

The means shown for controlling the position of the space-closing ring-structure described, comprise a plurality of levers 58, 110 shown as four in number, which are pivotally connected, between their ends, with the ring 46, by pivot pins 59 supported in pairs of ears 60 on this ring. These levers which are grouped about the axis of the shaft 13, oppose, at their outer end portions 61, adjustable abutments on the cover section 18, shown in the form of screws 62 carried by this cover, whereby when these levers are rocked in one direction, the engagement of their portions 61 with the abutments 62 operates to force the space-closing ring-structure referred to in a direction to close said space. The inner ends of the levers 58 are formed 115 with inwardly-extending, angularly-disposed, fingers 63, which extend into an annular groove 64 provided in the circumferential surface of an annular member 65 surrounding the shaft 13 and opposing a flange 66 on a collar 67 surrounding, and secured 120

at 68 to, a sleeve 69 keyed to the shaft 13 to be movable lengthwise of the latter and rotate therewith. The inner end of the sleeve 69 is circumferentially enlarged, as represented at 70 to provide an annular shoulder 71 between which and the member 65 the races and balls of a ball-bearing 72 surrounding the collar 69, are confined, whereby the member 65, sleeve 69 and collar 67 are so associated that lengthwise movement of the sleeve 69 operates to correspondingly shift the member 65 lengthwise of the shaft 13 and consequently actuate the levers 58.

Surrounding the member 65 and confined between the cover-plate 18 and the portion of the member 65 in which the groove 64 is presented, is a spiral spring 73, the tension of which is such as to force, unless restrained by the shifting mechanism hereinafter referred to and cooperating with the sleeve 69, the member 65 to the left in Fig. 1 to the position therein shown, and consequently the ring-structure formed of the rings 44, 45 and 46 to the position shown in this figure to close, and maintain closed, the space in which the piston-blades 42 are located.

The sleeve 69 may cooperate with any suitable means for effecting, under the control of the operator, the shifting of this sleeve to the right in Fig. 1, and relieving the pressure on the space-closing ring-structure so that this structure may move to space-opening position, the means shown comprising the mechanism commonly employed in automobile construction for operating the clutches thereof and comprising a rock-shaft 74 journaled in any desirable manner on a stationary part of the car and operated in any desirable manner by the operator, the shaft 74 being provided with a pair of fingers 75 rigid thereon and provided with roller-equipped pins 76 which bear against a face of a thrust-ring 77 surrounding the sleeve 69, with a thrust ball-bearing 78 confined between this sleeve and a nut 79 secured on the outer end of this sleeve, this nut, as is the usual practice in clutch mechanisms of automobiles, being movable, in the actuation of the shaft 74 to throw out the clutch, into frictional engagement with a stationary member, represented at 80, and presenting a brake-face for engaging this nut, to arrest rotation of the driven shaft 13 following the act of unclutching this shaft 13 from the drive-shaft 9.

In the use of the mechanism, oil or any other suitable liquid is charged into the interior of the casing formed of the shell 16 and cover-plate 18, and assuming the drive-shaft 9 to be rotating, the oil, by centrifugal force, is caused to extend in the form of a band at the inner circumference of this casing, the amount of oil charged into the casing being preferably sufficient to cause it,

under the centrifugal action referred to, to cover the joint between the ring section 44 and the shell 16.

Assuming that the shaft 74 is actuated to shift the ring structure formed of the rings 44, 45 and 46 to the right in Fig. 2 to open the side of the space in which the blades 42 extend, no effective pumping action on the oil is produced and no imprisoning thereof between adjacent blades 42 is effected and consequently the rotary member 33 does not become clutched to the rotating shell 16 and this shell thus rotates without driving the member 33 and shaft 13.

It may be here stated that in the rotation of the member 16 it is required that suction action be produced on the oil to imprison a charge between adjacent ones of the blades for effecting the driving action and therefore, to effect the driving action, it is necessary not only that the space in which the blades 42 operate, be closed to the air in the casing formed of the shell 16 and cover plate 18 so that oil will be pumped, but also that this space be closed against escape of oil therefrom, and to avoid "grabbing" of the clutch the element controlling the escape of the oil should close relatively slowly, and this result is effected by the sectional ring structure described, the inner ring section 45 controlling communication between the space in which the blades 42 operate and the space within the casing exterior thereof and filled with air, and the ring section 44 controlling the escape of oil from the space in which these blades operate.

When the operator releases pressure on the shaft 74, permitting the spring 73 to force the ring-structure referred to into a position for closing the open side of the space in which the blades 42 are located, this space becomes closed, except for the port 28, by the ring sections 45 and 44 seating in succession, and continued rotation of the shell 16 causes the oil sucked into this space through the port 28, by the action of the blades 42, to fill this space between the one of the blades 42 across which the port 28 is moved and the one of the blades next in advance thereof. As the shell 16 continues to rotate the port 28 passes beyond both of these last-referred-to blades, and as there is no outlet for the oil disposed between these blades, as soon as the shell 16 is rotating relative to the member 33 reaches a point where the space between these two blades 42 is of less volume than the volume of this space at the instant the port 28 moves beyond both of these blades, the oil imprisoned between these two blades, and not being compressible, the member 33 and consequently the shaft 13 become clutched to the driving shell 16 through the medium of this imprisoned oil. As soon as the space closing ring-structure referred to is moved

100
105
110
115
120
125
130

by the operator to the right in Fig. 2 to open the side of the space containing the blades, the oil is free to escape from this space and, depending upon the extent to which the ring structure is moved as stated, the drive of the member 33 from the shell 16 is correspondingly affected, it being possible by the arrangement shown to vary the degree of "slippage" of the shell 16 relative to the member 13 to vary the speed at which this member is driven relative to the shell 16, by varying the position of the ring-structure referred to.

The provision of the sectional ring-structure described, whereby the air is first shut off from the space in which the blades 42 operate, and then escape of oil therefrom prevented, causes the clutch to take hold slower than if a single ring structure were provided, which simultaneously shuts off the inlet of air to the space referred to and the outflow of oil therefrom.

To further delay the movement of the ring section 44 to closed position after the ring section 45 has seated, I provide a delaying mechanism which, in the particular illustrated embodiment of my invention, is of the dashpot type and comprises an annular groove 81 in a face of the hub of the member 33, containing a port 81^a; and in which groove a concentric flange or piston member, 82 on the inner end of the sleeve 69 is movable with the sleeve 69, lengthwise of the shaft 13, the port 81^a opening into one end of a tube 83 (Fig. 6) the other end of which opens into a hollow head 84 carried thereby and provided with an inlet 85 controlled by an inwardly-opening ball check-valve 86 and also provided with a bleeder-opening 87, this head extending in such a position, as shown that it will be immersed at all times in the oil in the casing during the rotation of the shell 16.

The port 81^a is preferably so arranged that as the dashpot piston 82 starts to cover it in moving inwardly the inner ring 45 will seat and close off the air. Thus the movement of the ring 44 to seating position, which takes place while the piston is moving across the port 81^a and after it has passed this port a slight distance is comparatively slow and gradually shuts off escape of the oil from the pumping space in which the blades 42 are located, it being understood that the piston 82 would not fit the walls of the groove 81 so tightly that there could not be slow leakage so that the piston can move inwardly beyond the port 81^a.

In operation, the sleeve 69 is cushioned in moving to the left in Fig. 2 to the position therein shown, first, owing to the restricted flow of the oil from the groove 81 out through the bleeder 87, the port 81^a being fully uncovered and the main outlet 85 of

the head 84 being closed by the valve 86 under the pressure against it of the oil in this head; and then further and more effectively cushioned to reduce its speed of movement, by the passage of the piston 82 across, 70 and beyond, the port 81^a.

As means for ensuring a supply of oil for entry into the head 84, I provide a passage 36^a in the flange 38 which is located at the joint between the ring sections 44 and 45 and 75 through which oil is forced into the channel provided by the flanges 37 and 38 in the movement of the ring section 44 to closed position, after the ring section 45 has closed.

It will be understood that the dashpot arrangement described may be used to advantage with a single ring-structure as the ring moves less rapidly to closed position by the use of dashpot mechanism than if such mechanism were omitted. The dashpot mechanism, however, is especially advantageous in connection with a plural ring-structure of the character described, and for the reasons as will be manifest from the foregoing description.

It will further be understood that by splining the blade-carrying member on the shaft 13, this member may move lengthwise of the shaft toward and away from the casing 16, and thus in the movement of the parts of the mechanism to effect the unclutching of the clutch elements, as above described, the blade-carrying member may bodily move to the right in Fig. 2, and thus friction between the relatively rotating parts is practically eliminated, it being understood that in the movement of the parts to clutching position the blade-carrying member is forced toward the member 16 and into close joint-forming condition to prevent escape of 105 the oil imprisoned between the blades 42.

The feature of providing the chamber 24 which extends outwardly beyond the chamber in which the pistons 42 extend and porting it as stated, is of advantage as it minimizes drag on the driven shaft. By providing this outside chamber the oil, in the unclutched condition of the parts and under centrifugal action, is caused to extend therein, and at least as to a great portion thereof, 110 not in a position in which it is engaged by the pistons. Thus in the relative movements of the parts in unclutched condition, the pistons are not required to pump oil, which 115 pumping action would produce drag on the 120 driven shaft.

While I have illustrated and described a particular construction embodying my invention, I do not wish to be understood as 125 intending to limit it thereto as the same may be variously modified and altered without departing from the spirit of my invention. What I claim as new, and desire to secure by Letters Patent, is:

1. In a hydraulic clutch, the combination 130

- of a driving element, a driven element, one of said elements having a portion rigid therewith and containing a laterally opening chamber the inner peripheral wall of which is eccentric to the axis of the other of said elements, pistons operatively connected with said last-referred-to element and extending into said chamber, and a ring movable toward and away from the open side of said 10 chamber for controlling the closing thereof.
2. In a hydraulic clutch, the combination of a driving element, a driven element, one of said elements presenting a casing and a portion rigid therewith and containing a 15 chamber which opens laterally into said casing, the inner peripheral wall of said chamber being eccentric to the axis of the other of said elements, pistons connected with said last-referred-to element and extending into 20 said chamber, and a ring in said casing movable toward and away from the open side of said chamber for controlling the closing thereof.
3. In a hydraulic clutch, the combination 25 of a driving element, a driven element, one of said elements containing a laterally opening chamber the inner peripheral wall of which is eccentric to the axis of the other of said elements, pistons operatively connected 30 with said last-referred-to element and extending into said chamber, and a ring movable into and out of a position for closing the open side of said chamber and comprising concentric sealing-ring sections relatively 35 movable in a direction lengthwise of the axes of said elements.
4. In a hydraulic clutch, the combination 40 of a driving element, a driven element, one of said elements containing a laterally opening chamber the inner peripheral wall of which is eccentric to the axis of the other of said elements, pistons operatively connected with said last-referred-to element and extending into said chamber, and a ring movable 45 into and out of a position for closing the open side of said chamber and comprising concentric sealing-ring sections relatively 50 movable in a direction lengthwise of the axes of said elements, and means yieldingly holding the inner one of said sections in an advanced position relative to the other one of said sections, whereby said inner ring section occupies sealing position before said outer section.
5. In a hydraulic clutch, the combination 55 of a driving element, a driven element, one of said elements containing a laterally opening chamber the inner peripheral wall of which is eccentric to the axis of the other of said elements, pistons operatively connected with said last-referred-to element and extending into said chamber, and a ring movable into and out of a position for closing the open side of said chamber and comprising concentric sealing-ring sections relatively 60 movable in a direction lengthwise of the axes of said elements, and means yieldingly holding the inner one of said sections in an advanced position relative to the other one of said sections, whereby said inner ring section occupies sealing position before said outer section.
6. In a hydraulic clutch, the combination 65 of a driving element, a driven element, one of said elements containing a chamber having an opening, the inner peripheral wall of said chamber being eccentric to the axis of the other of said elements, pistons operatively connected with said last-referred-to element and extending into said chamber, means movable into and out of a position for sealing the opening in said chamber, means tending to move said first-named means to sealing position, and dash-pot mechanism 70 for cushioning said first-named means in its movement to sealing position.
7. In a hydraulic clutch, the combination 75 of a driving element, a driven element, one of said elements containing a laterally opening chamber the inner peripheral wall of which is eccentric to the axis of the other of said elements, pistons operatively connected with said last-referred-to element and extending into said chamber, means movable 80 into and out of a position for sealing the open side of said chamber, means tending to move said first-named means to sealing position, and dash-pot mechanism 85 for cushioning said first-named means in its movement to sealing position.
8. In a hydraulic clutch, the combination 90 of a driving element, a driven element, one of said elements containing a chamber having an opening, the inner peripheral wall of said chamber being eccentric to the axis of the other of said elements, pistons operatively connected with said last-referred-to element and extending into said chamber, means movable 95 into and out of a position for sealing the opening in said chamber, means tending to move said first-named means to sealing position, and dash-pot mechanism for cushioning said first-named means in its movement 100 to sealing position.
9. In a hydraulic clutch, the combination 105 of a driving element, a driven element, one of said elements containing a chamber having an opening, the inner peripheral wall of said chamber being eccentric to the axis of the other of said elements, pistons operatively connected with said last-referred-to element and extending into said chamber, means movable 110 into and out of a position for sealing the opening in said chamber, means tending to move said first-named means to sealing position, and dash-pot mechanism for cushioning said first-named means in its movement 115 to sealing position comprising a tube communicating with the cylinder of said dash-pot mechanism and opening into the body of oil at the circumferential portion of the clutch.
10. In a hydraulic clutch, the combination 120 of a driving element, a driven element, one of said elements containing a laterally opening chamber the inner peripheral wall of which is eccentric to the axis of the other of said elements, pistons operatively connected with said last-referred-to element and extending into said chamber, means movable 125 into and out of a position for sealing the open side of said chamber, means tending to move said first-named means to sealing position.

- ing position, and dash-pot mechanism for cushioning said first-named means in its movement to sealing position comprising a tube communicating with the cylinder of 5 said mechanism and opening into the body of oil at the circumferential portion of the clutch.
10. In a hydraulic clutch, the combination of a driving element, a driven element, one of said elements containing a laterally opening chamber the inner peripheral wall of which is eccentric to the axis of the other of said elements, pistons operatively connected with said last-referred-to element 15 and extending into said chamber, means movable into and out of a position for sealing the open side of said chamber, means tending to move said first-named means to sealing position, and dash-pot mechanism for cushioning said first-named means in its movement to sealing position and provided with a main inlet and a bleeder, and a valve for checking out-flow through said main inlet.
11. In a hydraulic clutch, the combination of a driving element, a driven element, one of said elements containing a laterally opening chamber the inner peripheral wall of which is eccentric to the axis of the other 20 of said elements, pistons operatively connected with said last-referred-to element and extending into said chamber, a ring movable into and out of a position for closing the open side of said chamber and comprising 25 concentric sealing-ring sections relatively movable in a direction lengthwise of the axis of said elements, means yieldingly holding the inner one of said sections in an advanced position relative to the outer one of 30 said sections, whereby said inner section occupies sealing position before said outer section, means tending to move said rings to sealing position, and dash-pot mechanism for cushioning said ring sections in their 35 movement to sealing position.
12. In a hydraulic clutch, the combination of a driving element, a driven element, one of said elements containing a laterally opening chamber the inner peripheral wall of 40 which is eccentric to the axis of the other of said elements, pistons operatively connected with said last-referred-to element and extending into said chamber, a ring movable into and out of a position for closing the open side of said chamber and comprising 45 concentric sealing-ring sections relatively movable in a direction lengthwise of the axis of said elements, means yieldingly holding the inner one of said sections in an advanced 50 position relative to the outer one of said sections, whereby said inner section occupies sealing position before said outer section, means tending to move said rings to sealing 55 position, and dash-pot mechanism for cushioning said ring sections in their movement to sealing position, the cylinder of said mechanism containing a port in communication with the supply of oil in the clutch, and the parts being so constructed and arranged that said port is covered by the piston of 60 said mechanism substantially simultaneously with the seating of said inner ring section in sealing position.
13. In a hydraulic clutch, the combination of a driving element, a driven element, one of said elements containing a laterally opening chamber the inner peripheral wall of which is eccentric to the axis of the other of said elements, pistons connected with said last-referred-to element and extending into 65 said chamber, said last-referred-to element containing a channel at its inner periphery, means movable into and out of a position for sealing the open side of said chamber, means tending to move said first-named means to sealing position, and dash-pot mechanism for cushioning said first-named means in its movement to sealing position comprising a tube communicating with the cylinder of 70 said dash-pot mechanism and opening into 75 said channel, a wall of said channel containing a port positioned to receive oil displaced by said first-named means in moving to sealing position.
14. In a hydraulic clutch, the combination of a driving element, a driven element, one of said elements containing a chamber having an opening, the inner peripheral wall of 80 said chamber being eccentric to the axis of the other of said elements, pistons operatively connected with said last-referred-to element and extending into said chamber, and closure-means movable relative to said piston-equipped element toward and away from 85 said chamber for controlling the opening 90 thereof, said piston-equipped element being movable toward and away from the other of said elements.
15. In a hydraulic clutch, the combination of a driving element, a driven element, one of said elements containing a laterally opening chamber the inner peripheral wall of which is eccentric to the axis of the other of said elements, pistons operatively connected with said last-referred-to element and 95 extending into said chamber, and closure-means movable relative to said piston-equipped element toward and away from 100 said chamber for controlling the open side thereof, said piston-equipped element being 105 movable toward and away from the other of said elements.
16. In a hydraulic clutch, the combination of a driving element, a driven element, a shell connected with one of said elements 110 and containing a chamber the inner peripheral wall of which is eccentric to the axes of said elements, a member closing the open side of said shell, said shell containing a 115 passage at its circumference provided with 120

a port which opens into said chamber and with a port which opens into the space beyond said chamber, a rotatable member carried by, and in driving engagement with, the other of said elements, said rotary member being movable lengthwise of the element on which it is carried, pistons mounted on said rotary member for radial movement, said pistons extending into said chamber, a ring structure for sealing the open side of said chamber and comprising a plurality of concentric rings movable lengthwise of the axes of said elements, said ring sections being relatively movable lengthwise of said axes, spring means yieldingly holding the inner one of said ring sections in a position in advance of the other of said ring sections, whereby said inner ring section seats to sealing position before the other of said ring sections, means yieldingly forcing said ring sections to sealing position, and dash-pot mechanism for cushioning the movement of said rings to sealing position.

17. In a hydraulic clutch, the combination of a driving element, a driven element, one of said elements containing a laterally opening chamber the inner peripheral wall of which is eccentric to the axis of the other of said elements, pistons operatively connected with said last-referred-to element and extending into said chamber, and means for closing the open side of said chamber comprising relatively movable sealing elements controlling the closing of said chamber to the flow of air and to the outlet of oil therefrom, respectively.

18. In a hydraulic clutch, the combination of a driving element, a driven element, one of said elements containing a laterally opening chamber the inner peripheral wall of which is eccentric to the axis of the other of said elements, piston operatively connected with said last-referred-to element and extending into said chamber, and means for closing the open side of said chamber comprising sealing elements relatively movable in a direction lengthwise of the axis of said elements and controlling the closing of said chamber to the flow of air and to the outlet of oil therefrom, respectively.

19. In a hydraulic clutch, the combination of a driving element, a driven element, one of said elements containing a laterally opening chamber the inner peripheral wall of which is eccentric to the axis of the other of said elements, pistons operatively connected with said last-referred-to element and extending into said chamber, and means for closing the open side of said chamber comprising relatively movable sealing elements controlling the closing of said chamber to the flow of air and to the outlet of oil therefrom, respectively, and means for yieldingly holding said air-controlling sealing ele-

ment in such position as to cause it to seat before said oil-controlling sealing element seats.

20. In a hydraulic clutch, the combination of a driving element, a driven element, one of said elements containing a laterally opening chamber the inner peripheral wall of which is eccentric to the axis of the other of said elements, pistons operatively connected with said last-referred-to element and extending into said chamber, and means for closing the open side of said chamber comprising relatively movable sealing elements controlling the closing of said chamber to the flow of air and to the outlet of oil therefrom, respectively, means for yieldingly holding said air-controlling sealing element in such position as to cause it to seat before said oil-controlling sealing element seats, and means for retarding the movement of said oil-controlling sealing element to sealing position after said air-controlling sealing element seats.

21. In a hydraulic clutch, the combination of a driving element, a driven element, one of said elements containing a laterally opening chamber the inner peripheral wall of which is eccentric to the axis of the other of said elements, pistons operatively connected with said last-referred-to element and extending into said chamber, and a ring supported on said chamber-equipped element and rotatable therewith and movable back and forth on said chamber-equipped element to control the closing of said chamber.

22. In a hydraulic clutch, the combination of a driving element, a driven element, one of said elements containing a chamber having an opening, the inner peripheral wall of said chamber being eccentric to the axis of the other of said elements, means operatively engaging said last-referred-to element and extending in said chamber and adapted to hydraulically clutch said elements together when said opening in said chamber is closed, said means being movable axially in said chamber, and closure means movable relative to said first-named means toward and away from said chamber for controlling the opening therein and forcing said last-named means into fluid tight condition.

23. In a hydraulic clutch, the combination of a driving element, a driven element, one of said elements containing a chamber having an opening, the inner peripheral wall of said chamber being eccentric to the axis of the other of said elements, piston means engaging said last-referred-to element and extending into said chamber and adapted to hydraulically clutch said elements together when said chamber-opening is closed, the one of said elements containing said chamber containing at its periphery a second chamber having a port which opens into said first-

named chamber, and means controlling the opening and closing of said chamber-opening.

24. In a hydraulic clutch, the combination of a driving element, a driven element, one of said elements having a casing divided into two chambers one of which is at the periphery of the casing and the other of which extends inwardly thereof with its wall eccentric to the axis of the other of said elements, said last-referred-to chamber opening laterally into the space in said casing therebeyond, piston means engaging said

last-referred-to element and extending into said second-referred-to chamber and adapted to hydraulically clutch said elements together when the open side of said last-referred-to chamber is closed, said peripheral chamber having a port opening into said second-referred-to chamber and a port opening into the space in said casing therebeyond, and means controlling the opening and closing of the open side of said second-referred-to chamber.

EDWARD S. PALMBLA.
